UNITED STATES PATENT OFFICE.

HILRY M. TUCKER, OF FORT WORTH, TEXAS.

BORING MACHINE.

Application filed April 2, 1921. Serial No. 457,983.

To all whom it may concern:

Be it known that I, HILRY M. TUCKER, a citizen of the United States, residing at Fort Worth, in the county of Tarrant and State 5 of Texas, have invented new and useful Improvements in Boring Machines, of which the following is a specification.

The object of my present invention is the provision of a simple and highly efficient 10 portable machine for boring and cutting stumps with a view to the expeditious removal of the major portions of the stumps from the ground.

To the attainment of the foregoing, the 15 invention consists in the improvement as hereinafter described and definitely claimed.

In the accompanying drawings, forming part of this specification:—

Figure 1 is a side elevation of a machine 20 constructed in accordance with my invention.

Figure 2 is a top plan view of the same.

Figure 3 is a rear end elevation of the machine.

25 Figure 4 is a top plan view of a modified machine hereinafter explicitly referred to.

Figure 5 is an enlarged fragmentary view 30 showing the lower section of the rockable casing and the driving connections of the battery of augers.

Figure 6 is a cross-section on the line 6—6 of Figure 5.

Figure 7 is an enlarged horizontal section 35 through the yoke and several augers in the plane indicated by the line 7—7 of Figure 1.

Figure 8 is an enlarged fragmentary view showing the manner of connecting the augers with the handle.

Similar numerals designate corresponding 40 parts in Figures 1-3 and 5-8 to which reference will first be made.

Among other elements my novel machine comprises a body 1. This body 1 is preferably, though not necessarily, equipped with 45 wheels 2 and is adapted to be drawn or otherwise moved from stump to stump.

Fixed to and rising from the body 1 are standards 3, and journaled and held against endwise movement in said standards is a 50 longitudinal shaft 4 in which is a longitudi-

nal key-way 5. At its rear end the said shaft 4 is connected with the drive shaft 6 of an internal combustion motor 7 which is mounted on the rear portion of the body 1 and provided with an oil tank 8, a tank 9 for 55 cooling water, and the other appurtenances of an internal combustion motor.

Receiving and supported by the shaft 4 is a casing made up of a lower section 10 and an upper section 11 bolted to or otherwise connected with the section 10. Keyed on the shaft 4 and spaced apart in the casing referred to by sleeves 12, Figure 5, are worm gears 13, and also arranged in the casing are worm gears 14 which are intermeshed with the gears 13. The gears 14 surround shafts 15, movable endwise through the casing and through the gears 14, and each gear 14 is provided with a key 15 disposed in a keyway 16 in its respective 70 shaft 15. At their upper ends the several shafts 15 are journaled in and connected to a handle 17 anti-friction thrust-bearings 18 being interposed between the underside of the handle 17 and abutments 19 on the shafts 75 as clearly shown in Figure 8.

The alternate shafts 15 are shorter than the other shafts 15 in about the proportion illustrated, Figure 1, and each shaft 15 is provided at its lower end with a chuck 20 80 to receive and hold the upper end of an auger; the augers of the short shafts 15 being numbered 21, and the augers of the long shafts 15 being numbered 22. At 23 is a two-part yoke that connects the battery 85 of shafts 15 and augers 21 and 22, and is adapted to be moved downwardly and upwardly with said battery. By comparison of Figures 1 and 7 it will be understood that the yoke 23 receives the lower portions 90 of the long shafts 15 and also receives reduced intermediate portions 24 of the augers 21 on the short shafts 15; also, that upright anti-friction rollers 25 are carried in the yoke 23 and surround the long shafts 15 and 95 the said reduced portions 24 of the augers 21 on the short shafts 15. It will be further noted by particular reference to Figure 7 that the augers 21 on the short shafts 15 overhang the contiguous portions of ad- 100

joining augers 22 and consequently the battery of augers 21 and 22 is adapted to make a cut in a stump much larger than the yoke 23 and through which said yoke 23 can be 5 freely moved downwardly and upwardly. The relative arrangement of the lower augers 22 and the upper augers 21 as described is also advantageous inasmuch as it enables the upper augers 21 to cut and remove the 10 stump portions left by the lower augers 22.

The casing made up of the connected sections 10 and 11 is preferably oil-tight so as to enable the intermeshed gears 13 and 14 to rest and work in oil or grease, and appropriate washers in the form of flanged sleeves 30, Figure 5, are interposed between the sections 10 and 11, on the one hand, and the shaft 4, on the other, with a view to preventing leakage of lubricant from the casing. 20

By lateral push or pull exerted on the handle 17, the shafts 15 together with the casing and the gears 14 are adapted to be swung as a unit on the shaft 4 so that the battery of augers can be swung from the pendent position shown by full lines in Figure 3 to that shown by dotted lines in said figure, and vice versa.

The practical operation of my novel machine will be readily understood by reference to Figure 1 when it is stated that the machine is first positioned at one side of a stump 40 to make a diagonal cut 41 therein, and is then positioned at the opposite 25 side of the stump to make a diagonal cut 42 therein, after the manner illustrated by dotted lines in said figure. Inasmuch as each of the cuts referred to is two and a half or three feet long; and the cuts 41 and 40 intersect each other at the point 43, it follows that the upper portion of the stump above and below the ground will be segregated from the lowermost portion of the stump and divided into three parts all of 45 which may be readily removed.

In the modification shown in Figure 4 the wheeled body 1^a is adapted to be connected through a draw-bar 50 with a tractor (not shown) for moving the machine, and the shaft 4^a of the machine is connected 50 through intermeshed miter gears 51 with a shaft 52 on which is a pulley 53 to receive a driving belt (also not shown) from the tractor. With the exception that its 55 shaft 4^a is driven in the manner indicated which obviates the necessity of equipping it with a motor such as 7 in Figures 1-3, the embodiment shown in Figure 4 is similar to that shown in the other figures and 60 is possessed of all of the practical advantages ascribed to the latter.

It will be understood that in both embodiments of my invention the casing and its appurtenances are capable of being 65 moved as a unit in the direction of the

length of the shaft 4 or 4^a; also, that the shafts of the augers 21 are provided above said augers 21 with conveyors 21^x, designed and adapted to remove the cuttings.

I have entered into a detail description 70 of the construction and relative arrangement of parts embraced in the present and preferred embodiments of my invention in order to impart a full, clear and exact understanding of the said embodiments. I 75 do not desire, however, to be understood as confining myself to the said specific construction and relative arrangement of parts inasmuch as in the future practice of the invention various changes and modifications 80 may be made such as fall within the scope of my invention as defined in my appended claims.

Having described my invention, what I 85 claim and desire to secure by Letters Patent, is:—

1. In a boring and cutting machine, the combination of a support, a shaft mounted in bearings thereon, worm gears mounted on the shaft to turn therewith and be capable of movement longitudinally of the shaft, a casing mounted on the shaft and capable of longitudinal movement thereon, a battery of shafts extending through the casing and adapted to rotate and move endwise in the 95 casing, means connecting the said shafts of the battery, worm gears keyed to the shafts of the battery, and through which the said shafts are endwise movable, said worm gears being arranged in the casing and intermeshed with the first-named worm gears, and augers carried by the forward portions of the shafts of the battery.

2. In a boring and cutting machine, the combination of a support, a shaft mounted 105 in bearings thereon, worm gears mounted on the shaft to turn therewith and be capable of movement longitudinally of the shaft, a casing mounted on the shaft and capable of longitudinal movement thereon, a battery 110 of shafts extending through the casing and adapted to rotate and move endwise in the casing, means connecting the said shafts of the battery, worm gears keyed to the shafts of the battery and through which the said 115 shafts are endwise movable, said worm gears being arranged in the casing and intermeshed with the first-named worm gears, augers carried by the forward portions of the shafts of the battery, the alternate augers 120 in rear of the other augers, and a yoke in which the shafts of the forward augers together with the rear augers are journaled, said yoke embracing the shanks or reduced portions of all of the augers but the rear 125 augers having vanes in rear of the reduced portions embraced by the yokes.

3. In a boring and cutting machine, the combination of supporting means, a shaft 130 therein, worm gears on the shaft and rota-

table thereby, means rockable on the shaft, a battery of shafts rotatable and movable endwise in said rockable means and rockable therewith, worm gears keyed to the 5 shafts of the battery and carried by the rockable means and through which the said shafts are endwise movable, said gears be-

ing intermeshed with the first-named gears, means connecting the shafts of the battery, and augers carried by the forward portions 10 of said battery shafts.

In testimony whereof, I affix my signature.

HILRY M. TUCKER.
